UNITED STATES PATENT OFFICE.

CARLOS HOLLY, OF LOCKPORT, NEW YORK.

METAL-PLANING MACHINE.

SPECIFICATION forming part of Letters Patent No. 394,363, dated December 11, 1883.

Application filed September 14, 1887. Serial No. 249,677. (No model.)

To all whom it may concern:

Be it known that I, CARLOS HOLLY, of Lockport, in the county of Niagara and State of New York, have invented new and useful Improvements in Metal-Planing Machines, of which the following is a specification.

This invention relates to that class of machines for planing metal in which the work to be planed is secured to a horizontal bed, which reciprocates under the cutting-tool.

The object of my invention is to improve the feed mechanism whereby the tool is moved preparatory to taking a new cut, in such manner as to render the feed positive and to reduce the dead motion of the reciprocating bed to a minimum.

My invention consists of the improvements which will be hereinafter fully described, and pointed out in the claims.

In the accompanying drawings, consisting of two sheets, Figure 1 represents a fragmentary side elevation of a planer provided with my improvements. Fig. 2 is a fragmentary horizontal section on line $x-x$, Fig. 1. Fig. 3 is a vertical cross-section on line $y-y$, Fig. 1. Fig. 4 is a similar view on line $z-z$, Fig. 1. Fig. 5 is a sectional elevation on line $x-x$, Fig. 3, showing the feed mechanism in position to be operated upon. Fig. 6 is a sectional rear elevation of the upper portion of the machine on line $w-w$, Fig. 1. Fig. 7 is a slight modification of the feed mechanism.

Like letters of reference refer to like parts in the several figures.

A represents the frame of the machine supported upon legs a .

A' represents standards arranged on both sides of the frame A and extending upwardly therefrom.

B represents the sliding bed provided on its under side with V-shaped guides b , moving in corresponding ways formed on the upper portion of the bed-frame A.

C represents the driving-shaft, which is provided with the usual tight and loose pulleys, whereby the bed B is moved alternately in opposite directions. The shaft C is supported in a suitable bearing at its outer end, and at its inner end in a bearing, c , formed on the bed A.

c' represents a pinion secured to the inner end of the driving-shaft C and meshing

with a gear-wheel, c^2 , secured to one end of a counter-shaft, c^3 , arranged below the driving-shaft and journaled in bearings c^4 in the lower portion of the frame A. The counter-shaft c^3 is provided at its opposite end with a gear-pinion, c^5 , meshing with a gear-wheel, D. The latter is secured to the feed-shaft d , which is arranged above the counter-shaft c^3 and carries the feed-pinion d' , which meshes with the feed rack-bar d^2 of the bed B in the usual manner. The wheels c^2 and D and portions of the shafts c^3 and d are shown in dotted lines in Fig. 3.

E represents a movable bar arranged longitudinally on one side of the machine and guided in ways e , formed in the lower inner side of one of the standards A', and held therein against vertical misplacement by angle-pieces e' . The bar E is provided at one end with a screw-threaded rod, e^2 , carrying a movable collar, e^3 .

F is a horizontal toothed segment pivoted by a stud, f , to a horizontal plate, f' , which connects the frame A and the standard A', which is arranged above the driving-shaft c . The segment F meshes with a pinion, f^2 , which is secured to the lower end of a vertical shaft, f^3 . The latter is seated at its lower end in a socket in the plate f' and journaled at its upper end in the standard A'.

$g-g'$ represent downwardly-projecting shoulders formed, respectively, on the outer and inner sides of the bar E; and g^2 g^3 are upwardly-projecting pins secured to the segment F and adapted to engage with the shoulders $g-g'$.

g^4 represents a laterally-projecting flange formed on the bed B, over the bar E, and provided with a row of openings, g^5 .

g^6 g^7 represent removable stops or pins inserted in the openings g^5 on opposite sides of the collar e^3 and projecting downwardly far enough to strike the collar and move the bar E and the parts connected therewith when the movable bed B has carried the work past the cutting-tool, thereby shifting the belts on the driving-pulleys and changing the direction of the movement of the bed B.

G represents the usual shipper-bar, which shifts the belts on the driving-pulleys of the shaft C and moves in a bearing, g^8 , secured to the standard A'.

g^9 represents a horizontal arm secured to

the upper end of the vertical shaft f^3 and connecting the latter with the shipper-bar G in such manner that the rocking motion of the shaft f^3 moves the shipper-bar to and fro.

- 5 H represents an upwardly-projecting cam-sleeve formed on the pinion f^2 , and provided on its upper side with a spiral surface. H' represents a similarly-shaped cam-sleeve moving loosely on the shaft f^3 and resting with its 10 lower spiral surface on the cam H, so that the rocking motion of the lower cam, H', causes the upper cam to rise and fall on the shaft f^3 . The cam H' carries an arm, h , which is pivoted at one end to the standard A' and connected at its opposite end by a spring, h^2 , to an arm, h^3 . The arm h^3 is pivoted at its rear end to the side of the bed B, and carries at its front end a depending link or slotted bar, h^3 .
- 20 I represents a short horizontal shaft journaled in a bearing, i , in front of the driving-shaft C. The bearing i forms part of a frame, i' , which is secured to the bed-frame A.
- I' represents a ratchet-wheel secured to the 25 inner end of the shaft I, and i^2 represents two elbow-levers hung loosely on the shaft I on opposite sides of the ratchet-wheel I' and carrying a pawl, i^3 , adapted to engage with the wheel I'.
- 30 i^4 represents a detent-pawl secured to the frame A and engaging at its free end with the ratchet-wheel I'.
- J represents a feed-finger pivoted with its bifurcated front end to the lower arms of the 35 pawl-levers i^2 , and guided in its vertical movement in a U-shaped guide, j , secured to the frame A.
- J' represents a milled or toothed feed-wheel secured to the driving-shaft C, and arranged 40 in rear of and in line with the feed-finger J.
- k represents a locking-finger pivoted between the outer pawl-lever and the adjacent branch of the bifurcated portion of the feed-finger J. The free end of the locking-finger 45 k is provided with a shoulder, k' , which is adapted to engage with a pin, k^2 , on the guide j , and thereby hold the feed-finger J out of engagement with the wheel J', as clearly shown in Fig. 1.
- 50 k^3 represents a spring connecting the locking-finger k with the feed-finger J, whereby the weight of the latter is added to the locking-finger k , to prevent the latter from disengaging from the pin k^2 .
- 55 l represents a laterally-projecting pin formed on the feed-finger J and engaging in the slotted link h^3 .
- M represents a stop-bar secured at its rear end to the lower end of the pawl-levers i^2 and 60 supported in a guide, m , secured to the frame A. The movement of the feed-finger J toward the feed-wheel J' is limited by a pin, m' , which strikes against the guide m . The pin m' is seated in one of a series of openings, m^2 , 65 formed in the stop-bar M.

N represents a bevel gear-wheel secured to the outer end of the shaft I and meshing with

a pinion, N', secured to the lower end of a vertical feed-shaft, n . The wheel N is preferably held on its shaft between two friction-collars, which hold the wheel firmly under ordinary conditions, but permit the wheel to slip when the tool encounters an abnormal obstruction. The feed-shaft n is seated at its lower end in a socket, N^2 , formed on the upper side of the bearing i , and is guided at its upper end in a bearing, n' , formed on the rear side of the vertical feed-slide n^2 , as clearly shown in Fig. 6. The slide n^2 is guided on the standards A' in the usual manner.

O represents the transverse slide moving on the vertical slide n^2 and carrying the cutting-tool O' in the usual manner. The transverse slide O is operated by the usual screw, o , and shaft o' . The drawings represent the 85 transverse feed-screw geared with the vertical feed-shaft n , so that the tool-holder is fed horizontally.

o^2 represents a gear-wheel which is secured to the screw o , and which meshes with a gear-wheel, o^3 , secured to a horizontal shaft, o^4 , which latter is provided with a bevel-pinion, o^5 . This pinion can be rotated in one or the other direction by two movable bevel-pinions, o^6 o^7 , mounted on the shaft n , and either of 95 which can be engaged with the pinion o^5 by hand-levers pp' , attached to the vertical slide. Each of the hand-levers p p' is provided with a locking-lever, p^2 , whereby the pinion can be locked in or out of engagement with the pinion o^5 .

The operation of my improved feed mechanism is as follows: In the position of the parts represented in Figs. 1 and 2 the sliding bed B and feed-wheel J' are moving in the direction indicated by the full-line arrows, the work indicated by dotted lines in Fig. 1 has moved past the cutting-tool, and the cut has been completed. The stop g^6 of the bed B now engages against the collar e^3 and moves 105 the bar E forwardly, causing the shoulder g' of the bar E to strike against the pin g^3 of the toothed segment F, and thereby swing the latter on its pivot forwardly. This movement of the segment F turns the pinion f^2 and the 110 shaft f^3 and shifts the belts on the driving-pulleys by the shipper-bar G, which latter is moved by the arm g . By thus shifting the belts on the driving-pulleys the bed B and feed-wheel J' are caused to move in the opposite direction, as indicated by dotted arrows 115 in Fig. 1. The same forward movement of the segment F causes the cam-sleeve H' to be elevated by the turning of the cam H, thereby raising the connected arms h h^2 . The first 120 part of the upward movement of the arm h^2 lifts the feed-finger J and locking-finger k by the link h^3 , thereby releasing the locking-finger k from the pin k^2 . The overhanging weight of the elbow pawl-levers i^2 throws the 125 feed-finger J backwardly against the face of the feed-wheel J' and causes the feed-finger to remain in contact with the feed-wheel during the movement of this wheel in the direc-

tion of the dotted arrow until the movement is stopped by the pin m' of the stop-bar M striking against the guide m , as represented in Fig. 5. The feed-finger J is now held in an elevated position slightly above the feed-wheel J' by the link h^3 . This upward movement of the feed-finger J causes the pawl i^3 to ride backwardly over the ratchet-wheel I' and take position for its next forward movement. The parts are held in this elevated position by the cam-sleeve H' until the bed B has moved backwardly sufficiently to cause the pin g^7 to strike against the collar e^3 and move the segment F in the opposite direction by the shoulder g of the bar E engaging against the pin g^2 of the segment, as shown in Fig. 1. This backward movement of the segment causes the pinion f^2 , cam H , and shaft f to rotate backwardly and shift the belts on the driving-pulleys, so as to move the bed B and feed-wheel J' in the direction of the full arrow in Fig. 1. This movement of the cam H allows the cam-sleeve H' , arm h , spring h' , arm h^2 , link h^3 , and feed-finger J to descend, thereby causing the latter to engage with the feed-wheel J' . The wheel J' now carries the finger J downwardly and backwardly until it is released and held out of engagement by the locking-finger k engaging over the pin k^2 of the guide j , as clearly shown in Fig. 7. This backward and downward movement of the finger J causes the pawl i^3 to engage with the ratchet-wheel I' and turn the latter forwardly, motion being transmitted from the ratchet-wheel through the shaft I and bevel-wheels N N' to the shaft n and from the shaft n to the feed-screw o by the bevel-wheels o^5 o^7 and gear-wheels o^3 o^2 . The movement so produced in the screw o causes the tool o' to be moved laterally ready for a fresh cut.

The feed movement is effected by my improved mechanism positively and as soon as the feed-finger comes in contact with the feed-wheel, thereby avoiding the slip and delay which take place at the beginning of the feed-motion, and the unnecessary expenditure of power after the feeding has been effected, as is the case with friction devices heretofore employed. This slip and delay necessitate the sliding bed to be moved a considerable distance beyond the cutting-tool before it can be reversed with safety, and this dead motion of the sliding bed entails a loss of time and power and unnecessary wear of the parts, which is avoided by my positively-acting mechanism.

The devices whereby the feed-finger is thrown into engagement with the feed-wheel may be modified without departing from my invention. For instance, the feed-finger may be provided with a spring, p^3 , which connects the finger with the frame or some other stationary part of the machine, and which tends to hold the finger against the face of the feed-wheel, as represented in Fig. 7. In this construction the finger rides loosely on the feed-wheel after it has reached the end of its

stroke, and when the feed-wheel reverses the finger is carried along by the feed-wheel until the finger reaches the opposite end of its stroke. This construction is, however, less desirable, because it produces noise by the finger riding on the roughened face of the feed-wheel after the finger has reached the limit of its movement. 75

I claim as my invention—

1. The combination, with the feed-wheel revolving alternately in opposite directions, of a feed-finger bearing against said feed-wheel and moved alternately in opposite directions by said feed-wheel, a tool-slide, and mechanism, substantially as described, whereby the tool-slide is actuated by the movement of the feed-finger, substantially as set forth. 80

2. The combination, with the reciprocating bed, the tool-slide, and its feed-screw, of a feed-wheel, a feed-finger engaging with said feed-wheel and moved alternately in opposite directions by said feed-wheel, a ratchet mechanism actuated by said feed-finger, and mechanism, substantially as described, whereby motion is transmitted from said ratchet mechanism to said feed-screw, substantially as set forth. 85

3. The combination, with the reciprocating bed, the tool-slide, and its feed-screw, of a feed-wheel, a feed-finger engaging with said feed-wheel and moved alternately up and down by the movement of the feed-wheel, a ratchet mechanism actuated by said feed-finger, and which actuates said feed-screw, and a locking-finger whereby the feed-finger is held out of engagement with the feed-wheel when said finger is in its lowest position, substantially as set forth. 90

4. The combination, with the reciprocating bed, the tool-slide, and its feed-screw, of a feed-wheel, a feed-finger engaging with said feed-wheel and actuated by the movement of the feed-wheel, a ratchet mechanism which is actuated by the feed-finger and which actuates said feed-screw, a locking-finger whereby the feed-finger is held away from the feed-wheel, and a lifting-lever whereby said locking-finger is released and the feed-finger engaged with the feed-wheel, substantially as set forth. 100

5. The combination, with the feed-wheel J' , of the feed-finger J , the locking-finger k , the locking-stop k^2 , pawl-lever i^2 , pawl i^3 , and ratchet-wheel I' , substantially as set forth. 115

6. The combination, with the feed-wheel J' , of the feed-finger J and the lifting-lever h^2 , provided with the slotted link h^3 , substantially as set forth. 125

7. The combination, with the feed-wheel J' , of the feed-finger J , the lifting-lever h^2 , provided with the slotted link h^3 , the arm h , connected with the lever h^2 , and the lifting-cams H H' , substantially as set forth. 130

8. The combination, with the feed-wheel J' , of the feed-finger J , the lifting-lever h^2 , provided with the slotted link h^3 , the arm h , connected with the lever h^2 , the lifting-cams H

- II', the pinion f^2 , the gear-segment F, meshing with said pinion and provided with stops $g^2 g^3$, and the movable bar G, provided with projections g^4 , substantially as set forth.
- 5 9. The combination, with the feed-wheel J', of the feed-finger J, the lifting-lever h^2 , provided with slotted link h^3 , the arm h , connected with the lever h^2 , the lifting-cams H II', the pinion f^2 , the gear-segment F, provided
10 with stops $g^2 g^3$, the movable bar G, provided with the adjustable collar e^3 , and the reciprocating bed B, provided with adjustable stops $g^6 g^7$, substantially as set forth.
10. The combination, with the feed-wheel J', of the feed-finger J, the lifting-lever h^2 , provided with the slotted link h^3 , the ratchet-wheel I', the pawl-levers i^2 , and pawl i^3 , the bar M, provided with stop m' , and the guide m , substantially as set forth. 15
